CLAIM

We claim the ornamental design for a computer, as shown and described.

DESCRIPTION

The present application is related to U.S. patent application Ser. No. 13/216,224 filed on the same day herewith by Britt C. Ashcraft, Eric Chen and Sandie N. Cheng and entitled Computing System Feet, the full disclosure of which is hereby incorporated by reference.

FIG. 1 is a bottom perspective view of a computer;

FIG. 2 is a bottom plan view thereof;

FIG. 3 is a right side view thereof;

FIG. 4 is a left side view thereof; and

FIG. 5 is a front elevational view thereof; and,

FIG. 6 is a rear elevational view thereof.

The dash-dash broken lines in the drawings are environmental lines which do not form part of the claimed design. The short dash-long dash lines are boundary lines which do not form part of the claimed design.
